(57) **CLAIM**

The ornamental design for module for multi-function equipment, as shown and described.

DESCRIPTION

FIG. 1 is a top perspective view of a module for multi-function equipment showing our new design;

FIG. 2 is a bottom perspective view thereof;

FIG. 3 is a top view thereof;

FIG. 4 is a bottom view thereof;

FIG. 5 is a front view thereof, the rear view being a mirror image; and,

FIG. 6 is a left side view thereof, the right side view being a mirror image.

The broken lines in the drawings represent environmental subject matter and form no part of the claimed design.
